UNITED STATES PATENT OFFICE.

ROBERT H. COMPTON, OF DUNNINGS, PENNSYLVANIA.

BUCKET AND BARREL PACKAGE.

SPECIFICATION forming part of Letters Patent No. 269,638, dated December 26, 1882.

Application filed November 13, 1882. (No model.)

To all whom it may concern:

Be it known that I, ROBERT H. COMPTON, of Dunnings, in the county of Lackawanna and State of Pennsylvania, have invented certain new and useful Improvements in Bucket and Barrel Packages; and I do hereby declare the following to be a full, clear, and exact description of the same, reference being had to the accompanying drawings, forming part of this specification, in which—

Figure 1 is a view showing the parts of the invention detached. Fig. 2 is a longitudinal vertical section of the package with all of the parts in position. Fig. 3 is a similar view with the parts put together in a different manner.

Similar letters of reference in the several figures denote the same parts.

My invention has for its object to provide an improved package for the storage and transportation of fruits, vegetables, butter, and other produce; and it consists of a package constructed and adapted for use substantially as I will now proceed to describe.

Referring to the drawings, A represents a barrel or similar vessel, which may be of wood, paper, or other material specially prepared for the purpose, or may consist simply of an ordinary wooden flour-barrel with its lower head, B, fitted into place, and having a central perforation, b, as shown. Extending through the perforations in the head B and up through the center of the barrel is a rod, C, having a suitable collar or cross-bar, e, at its lower end bearing against the outside of said head, as shown.

D D' are tubular sections, of wood, paper, or other suitable material, adapted to fit upon and cover the rod C within the barrel. E is an adjustable partition adapted to fit upon the rod C, and to be locked thereto by a set-screw, e, or equivalent device. F is the removable head of the barrel, through a perforation in the center of which passes the upper end of the rod C, and G is an eccentric clamp pivoted to the top of the head F, and adapted when turned to clamp and securely hold the rod C.

In fitting the parts of the package together the lower tubular section, D, the partition e, the upper tubular section, D', and the head F may each be slipped on the rod C in the order named, thereby forming a package having an

upper and lower compartment, each of which may contain and retain intact fruit, vegetables, or other produce of the same kind and quality, or of the same kind and different quality, or of different kinds. The central partition being secured by its set-screw to the rod sustains the weight of the material above it, thereby relieving the material below from undue pressure and consequent damage. Such central partition further divides the vessel, so that one or both may be filled wholly or partially while the other remains empty, as is obvious.

Instead of locating the partition so as to divide the package into two compartments, as above described, both tubular sections may be placed together and the partition set upon them, as indicated in Fig. 3, thus making a single-compartment package.

It is obvious that by increasing the number of tubular sections and adjustable partitions a package containing a larger number of compartments can be produced, if desired.

As applied to packages for containing butter and the like my invention will be found to be particularly useful. The tubular sections, besides operating to control the size of the compartments, completely cover the metal rod and leave no metal surface for the butter to come in contact with.

Other advantages than those enumerated will flow from the use of my invention, as will be apparent upon reflection.

When an ordinary barrel provided with my attachments is used for transportation purposes all the attachments can be removed and shipped back "knocked down" when the barrel reaches its destination, and the barrel left behind.

Instead of employing the eccentric cam G as a means for securing the rod C, the latter may be screw-threaded at its upper end, and a suitable screw-nut screwed upon the rod on the outside of the head F.

Having thus described my invention, I claim as new—

1. The herein-described transporting and storing package, consisting of the exterior shell or barrel having the fixed perforated head, the rod extending through the barrel, the tubular sections, the partition, the removable perfo-

rated head, and the means for securing the rod to the removable head, substantially as set forth.

2. The combination, with the exterior shell or barrel having the perforated fixed head, of the through-rod, the tubular sections, and the adjustable partition, with means for securing it to the rod at the appropriate point of ad-

justment, the whole arranged substantially as described.

ROBERT H. COMPTON.
